DELAWARE.

CHEEK PLATE.

Application filed May 11, 1922. Serial No. 560,175.

To all whom it may concern:

Be it known that we, BYERS W. KADEL and PERCY R. DRENNING, citizens of the United States, residing at Baltimore, in the State of Maryland, have invented certain new and useful Improvements in Cheek Plates; and we do hereby declare the following to be a full, clear, and exact description of the invention, such as will enable others skilled in the art 10 to which it appertains to make and use the same.

Our invention relates to cheek plates of the type employed in the well known form of draft rigging mechanism commonly designated as the Farlow two-key draft gear attachments.

This invention has for an object the provision of a strong, durable and easily applied cheek plate capable of effectively fulfilling the requirements of operating conditions, said cheek plate being formed with a plurality of key-receiving slots adapted to extend through a body web portion, said web portion being gradually tapered from each 25 end of the cheek plate toward the center to provide graduated cross sectional areas throughout the length of the cheek plate.

Another object of the invention consists in forming a cheek plate with a body web having a relatively flat inner face arranged to engage the outer face of the center sill, and an inclined outer face adapted to form with said inner face a varying cross sectional area throughout the length of the 35 cheek plate, said cross sectional area being relatively large at the central or intermediate portion of the cheek plate and adapted to diminish in net cross sectional area toward each end thereof.

40 A further object of the invention is to provide a cheek plate formed with a plurality of reinforced key-receiving slots, one of said slots having an inwardly projecting flange passing through the respective slot in the draft sills, and having a portion projecting inwardly thereof in close proximity to the yoke, and an outwardly projecting flange having an enlarged portion at one end adapted to form with said inwardly projecting portion a relatively large bearing area 50 for the key connecting the yoke and follower block of the cushioning mechanism.

The invention further consists in the combination, arrangement and construction of

the several parts hereinafter described and 55 pointed out in the claims.

In the drawings illustrating our invention: Figure 1 is a horizontal sectional view of a pair of cheek plates embodying the invention, showing the relation to the center sills 60 of a car and to the form of draft gear attachments with which they are especially suited.

Figure 2 is a view in side elevation of a portion of the outer face of one of the car 65 sills, showing the cheek plate attached thereto.

Figure 3 is a horizontal sectional view through the cheek plate.

The type of Farlow two-key draft gear 70 mechanism illustrated in the drawings, includes the car coupler 1 which is operatively connected to the draft yoke 2 by a transverse coupler key 3 which latter extends through a slot 4 in the shank of the coupler, 75 thence through the elongated slots 5 provided at the forward ends of the yoke arms, and then through the key receiving slots of our improved cheek plate 6 connected to the center or draft sills 7 of the car underframe. Associated with the coupler and at the rear of the shank thereof, is arranged the follower block 8 having a slot 9 adapted to receive the key 10, said key being adapted to pass through elongated slots 11 provided in the 85 arms of the yoke, and projecting into another series of key-receiving slots formed in the cheek plates 6 fitted to the draft sills.

It will be understood by those skilled in the art that the car coupler 1, upon performing a buffing operation, causes the follower block 8 and the two keys 3 and 10, respectively, to travel rearwardly into corresponding slots of the cheek plates and of the draft yoke, the latter being prevented from retreating by means of a suitable backstop or by abutments (not shown), rigidly connected to the car. When, however, the coupler 1 is pulled outwardly the key 3 draws the yoke 2 along with it while the rear key 10, 90 by bearing against the cheek plates at the forward ends of their slots, arrests the follower block 8 and transfers the pressure to which the latter is subjected to the cheek plates and thence to the center sills or draft 95 sills. While my present form of cheek plates is particularly adapted for use in conjunction with the particular type of draft 100

gear attachments which have been described, it is to be understood that these special details of construction are not disclosed with the intention to limit cheek plates to use therewith.

Each cheek plate 6 is formed with a body web 12 having a relatively flat face adapted to contact the outer side of the center sills, and is provided with suitable openings whereby it may be rigidly attached to said sill by rivet means 13. The outer face of the body web of each cheek plate is gradually inclined or tapered from each end of the cheek plate to an intermediate portion to provide a maximum cross sectional area at or about a point adjacent the opposite inner ends of the key-receiving slots, as indicated by the numeral 14, the cross sectional area of the material being gradually diminished toward each end of the cheek plate to the normal cross sectional area of usual body web construction. In side elevation it will also be noted that the top and bottom edges of the cheek plate are reversely inclined or tapered from an intermediate point toward the ends thereof. With the exception of the outermost rivets at each end of the cheek plate, the great majority of the rivets 13 are maintained in horizontal alinement throughout the length of the cheek plate. Bosses are preferably provided on the outer face of the cheek plate, said bosses surrounding the rivet openings and being located at the respective points from the upper and lower edges of the cheek plates, as shown.

The bosses provide for the proper insertion of the rivets through the cheek plates without angular displacement thereof due to the graduated cross sectional area of said cheek plates.

Key-receiving horizontally alined slots 15 and 15' are provided in the cheek plates, the slots 14 being adapted to receive the projecting ends of the coupler key 3 and the slots 15' being arranged to receive the extending ends of the key 10 connecting the follower block and yoke. Projecting inwardly from the body web of the cheek plate and surrounding the key slot 15 is an inwardly extending flange 16 adapted to fit within and engage the edges of a slot 17 formed in the forward end of the center sill. The inwardly extending flange 16 is preferably adapted to terminate flush with the inner face of the center sill, as shown. An outwardly projecting flange 18 extends from the outer face of the body web of the cheek plate and, together with the inwardly extending flange 16, serves to form the slot 15. The respective ends of the slot 15 form stop portions for the respective forward and rear edges of the coupler key 3, as will be understood.

The key-receiving slot 15' in each cheek plate is provided with an inwardly extend-

ing flange 19, said flange being inclined forwardly, as shown, and adapted to extend inwardly of the draft sills into relative close proximity to the side arms of the yoke. An outwardly projecting flange 20 surrounds the key slot 15', said flange 20, together with the inwardly extending flange 19, forming a relatively large and strong key support and bearing for effectively receiving and transferring the strains to the draft sills. The forward portion of the outer flange 20 is enlarged and reinforced, a fillet 21 being provided for permitting clearance for the cotter in the use of a standard length key.

Diagonally arranged webs 22 serve to reinforce the forward portion of the outer flange 20 and the inner portion of the outer flange 18, a longitudinally arranged web 23 connecting said flanges at their respective inner ends, as shown. The outer flange 20 is reinforced at its opposite or rear end by means of diagonal webs 24, and a longitudinally disposed web 25, as shown. A longitudinally arranged web 26 is provided to reinforce the forward end portion of the flange 18. The reinforcing webs are advantageously positioned to brace the flanges receiving the buffing strains and imparting them to the car underframe. The outer flanges surrounding the respective key slots 15 and 15' are relatively thickened at each end, the reinforcing webs integrally uniting the body web portion of the cheek plate to the flanges, thereby providing for a strong construction with an advantageous distribution of the metal in obtaining maximum strength value with a minimum of material employed.

A cheek plate constructed in accordance with our present invention provides greatly increased key bearing area, said area being effectively braced by webs and also gradually reinforced by the intermediate increased cross sectional area of the body web of the cheek plate.

We claim:

1. A cheek plate formed of a body web portion of varying cross sectional area gradually increased from the ends of the cheek plate to an intermediate point and having a plurality of key receiving slots, the inner adjacent portions of said slots intersecting the greatest cross sectional area of the body web.

2. A cheek plate having a body web portion affording means for connecting it to the center sill or draft sill of a car and having a plurality of key receiving slots adapted to register with the slots formed in said car sill, said body web portion being formed of maximum cross sectional area at a point intersecting adjacent portions of said key receiving slots, and having opposite end portions of gradually diminishing cross sectional area.

3. A cheek plate including a body web affording means for connecting the cheek plate to the center sill of a car, said body web being formed of varying cross sectional area gradually increased from the ends of the cheek plate to an intermediate point and having a plurality of key receiving slots adapted to register with slots formed in said center sill, flanges surrounding said key receiving slots on the outer face of the cheek plate, and an inwardly extending flange having an inwardly projecting portion adapted to form with one of the flanges provided on the outer face of the cheek plate a relatively large key bearing portion located approximately intermediate the ends of the cheek plate.
4. A cheek plate including a body web affording means for connecting the cheek plate to the center sill of a car, said body web being formed of varying cross sectional area gradually increased from the ends of the cheek plate to an intermediate point and having a plurality of key receiving slots adapted to register with slots formed in said center sill, a flange surrounding each of said key receiving slots on the outer face of the cheek plate, and a projecting flange surrounding one of said key receiving slots and extending inwardly of the center sill to form with one of the flanges on the outer face of the cheek plate a key bearing portion of increased area.
5. A cheek plate including a body web of varying cross sectional area gradually increased from the ends of the cheek plate to an intermediate point and having a plurality of key receiving slots, an inwardly projecting flange surrounding one of said slots, said flange being inclined forwardly and inwardly of one face of the cheek plate, and an outwardly projecting flange having an enlarged portion adapted to form with the forward end of said inwardly inclined flange a relatively large key bearing surface at a point intersecting the intermediate cross sectional area of the cheek plate.
6. A cheek plate having a body web affording means for connecting it to the center sill or draft sill of a car, said body web having a flat inner face and an outer face oppositely inclined from an intermediate point toward each end to provide a central maximum cross sectional area gradually diminished toward the respective ends of the cheek plate.
7. A cheek plate having a body web affording means for securing it to the center sill of a car, said body web being formed of an intermediate increased cross sectional area and having a plurality of key receiving slots adapted to register with slots formed in said center sill, flanges surrounding said key receiving slots adapted to provide relatively large key bearing surfaces, and a plurality of webs projecting from said intermediate cross sectional area and uniting inner adjacent portions of said flanges.

In testimony whereof we affix our signatures.
